Primary Examiner — Stacia Cadmus(74) *Attorney, Agent, or Firm* — Plumsea Law Group, LLC(57) **CLAIM**

The ornamental design for a wheel for automobile, as shown and described.

DESCRIPTION

FIG. 1 is a front perspective view of a wheel for automobile; and,

FIG. 2 is a front elevation view thereof.

The broken lines shown in the drawings illustrate portions of the wheel that form no part of claimed design.
